CARBONIZATION OF LIGNITE

Fred Denig, Pittsburgh, Pa., assignor to Koppers Company, Inc., a corporation of Delaware

Filed Nov. 12, 1957, Ser. No. 695,792

2 Claims. (Cl. 208—8)

This invention relates generally to the carbonization of coal and more particularly to a method for carbonization of lignite and low grade coals.

It is an object of the present invention to provide a method of carbonizing lignite and low rank coals in a manner such that there will result a coal tar by-product having the characteristics of high-temperature tars.

Coal tars produced during the carbonization of coal are classified as either high-temperature tars or low-temperature tars. Of these two classes only high-temperature tars are of commercial significance. These coal tars are of an extremely complex mixture of organic compounds. The composition of the tar depends principally on the temperature of carbonization, but it is also influenced to a lesser extent by the nature of the coal which is coked. High-temperature tars, the most important commercially, contain large proportions of aromatic compounds; phenols, cresols, naphthalene, benzene and its homologues, and anthracene. They are produced by the cracking of the primary tars which result from the break-down of the coal structure itself during carbonization. The compositions of the latter are influenced to some extent by the coals from which they are produced, but it has been found that further heating tends to eliminate the differences and the final composition of the tar depends primarily on the conditions of decomposition.

Low-temperature carbonization yields tars which are less severely altered and which contain paraffins and some dihydroxy phenols, in addition to cresols, xylenols, still higher phenols, and alkylated naphthalenes. The variations in the composition of these tars are much greater than in those produced at the higher temperatures, because of differences in the degree of cracking of the primary compounds. These low-temperature tars are substantially useless commercially.

In the carbonization of lignite and low rank coals for the formation of coke suitable for use in the reduction of ores to produce a tar equivalent to that produced in high-temperature coke ovens the temperature at which the lignite is carbonized is about the same as the temperature required when carbonizing the high grade bituminous coal in conventional coke ovens.

Occasionally low-temperature carbonization of lignite and low grade coal is required such that a satisfactory coke is produced, but these low-temperature carbonizations have the drawback of producing a tar having the characteristics of a low-temperature tar.

In the carbonization of coal in the conventional slot-type coke oven the heat is applied to the coal through the outer coke oven wall. Coking proceeds from the oven wall to the vertical center of the coal charge. The entire coal charge is quickly coated by a layer of coke formed next to the heating walls and the gases and tars are forced through the coke mass against the hot walls and are further cracked giving a gas high in hydrogen content and the well known high-temperature tar at the oven gas outlet.

2

In one known method of carbonizing lignite, the lignite is initially pulverized and then dried in a first unit containing a fluidized bed and wherein the products of combustion of a specific amount of other lignite is charged through the unit. The hot solid lignite from the first unit is then fed to a second unit which is maintained at a higher temperature and contains another fluidized bed. The treatment of charging the products of combustion of the lignite through the fluidized bed as performed in the first unit is repeated. While the temperature in this second unit is maintained higher than the temperature in the first unit, this high temperature must sometimes be controlled such that it does not exceed the temperature at which the lignite breaks into powder and thereby fails to produce a suitable coke. These lower controlled temperatures result in a yield of a low-temperature tar.

By the present invention it is proposed to carbonize the lignite and low grade coal at the required temperatures for producing a coke suitable for the treatment of ore or the like, and also producing a tar having the characteristics of the aforementioned high-temperature tars.

Briefly, this is accomplished by the provision of a localized heating zone which is maintained at a temperature which will convert the volatile matter driven off during the carbonization of the coke formation.

More particularly, the carbonization of the lignite is accomplished with the assistance of electrical energy to provide a source of heat for the formation of coke and the volatile materials resulting therefrom the carbonization are passed through a bed of carbon or breeze coke which is also subjected to the electrical energy.

The above and further objects and novel features of the invention will hereinafter appear more fully from the detailed description when the same are read in conjunction with the drawing. It is to be expressly understood, however, that the drawings are not to be a definition of the invention but for the purpose of illustration only.

In the drawings where like parts are numbered alike; Fig. 1 is a vertical section through a retort arranged to carry out the present invention.

In accordance with the present invention, there is used a convenient carbonizing oven which may be in the form of a retort having located therein means for conducting electrical current therethrough for the purpose of providing the heat for carrying out the carbonization. The retort will be substantially filled with lignite or low grade coal, over the top of which will be superimposed a layer of carbonaceous material such as coke breeze or the like. The coke breeze will be arranged such that it is in contact with the electrical conducting means, whereby the current flowing therethrough will also be conducted through the carbonaceous material.

Referring now to Fig. 1 there is illustrated one form for carrying out the method of the present and may be a steel retort 10 of the type illustrated and disclosed in U.S. Patent 1,938,121 issued to H. Stevens. For the purpose of simplicity, only, the inner fire brick wall 11, upper end 13 and the hingedly connected bottom gate 15 are illustrated. It is to be understood, however, the retort 10 may be provided with flues formed about the wall through which heat gases may be circulated as provided in the Stevens patent to assist in heating the charge of lignite and rank coal to be carbonized.

Disposed within the retort 10, for the purpose of providing an internal heating unit, is an electrode 17 of which the bottom end is in engagement with the bottom gate 15 and is connected to a low potential source of current and the upper end is connected to a high potential source of current. The electrode 17 may be formed of any

suitable high resistance conductor which when current is passed therethrough will create sufficient heat to carry out the carbonization of lignite. Additional heat may also be provided by hot flue gases or the like which may be circulated about the retort 10 by suitable means well known in the art through the flues not shown.

Provided on the top 19 is a charging hole 21 through which the charge of material to be carbonized is introduced into the retort 10 and a tube 23 for taking off the volatile constituents evolved during the carbonization of the coal. 10

The above described structure is similar to that described in the aforementioned Stevens patent. While the Stevens apparatus operates satisfactorily for the production of coke, the temperatures created are such that low-temperature tars result therefrom, even when high grade 15 bituminous ores are carbonized.

By the present invention there is provided a means for converting these low-temperature tars to high-temperature tars. To this end, high resistance electrical conductors, which may be in the form of carbon formed bricks 27, are inserted in the brick wall 11 adjacent to the top 19. These bricks 27 are also connected to a source 20 of current.

In carrying out the present invention the lignite charge L is introduced into the retort 10 until it reaches the level of the powdered carbon bricks 27. Thereafter a coke breeze 29 is introduced into the charging hole 21. The coke breeze 29 is dispersed and superimposed over the top of the lignite as a layer and contacts the electrode 17 and the carbon bricks 27 thereby to form a porous surface electrode through which the vapors and gases driven off during the carbonization may pass. 25

Upon the passage of current through the retort, the heat is supplied to the charge of lignite L by the flow of current through the electrode 17, whereupon the portion of the charge adjacent to the electrode 17 becomes heated and in this manner also becomes coke and a conductor having a slight resistance and affords a greater electrode diameter which in turn heats the next adjacent area and so on until the entire charge is heated. In addition to the heat provided by the electrode 17, if desired, heat may be also supplied by the flue gases circulating about the wall 11 such that both the inner and outer charges of lignite are heated simultaneously. This 30 results in a rapid carbonization in which the resulting volatile matter and vapors if not treated further would result in coal tars having low-temperature characteristics. 40

The evolved volatile substances in the form of vapors and gases during this carbonization stage arise from the 45 50

lignite and pass upwardly through the layer of coke breeze 29 overlying the lignite. Since the coke breeze has a high resistance and is in contact with the electrode 17, the passage of current therethrough renders the coke breeze incandescent and creates a higher temperature than that of the underlying carbonization temperature. Hence, when the evolved gases pass through this localized high-temperature zone created by the layer of coal breeze 27, the volatile matter is further distilled such that substances taken off through the gas take-off tube 23 are converted to commercially usable high-temperature tars. 5

Variations and modifications may be made within the scope of the claims and portions of the improvements may be used without others.

I claim:

1. A process for carbonizing and distilling lignite for forming coke and coal tar which comprises heating said lignite to drive off the volatile constituents and to form coke, and passing said volatile constituents through a 20 localized heating zone formed by electrically conductive carbon particles, passing an electrical current through said carbon particles to heat said zone to incandescence to convert said volatile constituents so that upon condensation said volatile constituents form a coal tar having the characteristics of high-temperature tars.

2. A process for carbonizing and distilling lignite for forming coke and coal tar which comprises heating the lignite by the passage of electrical current therethrough to drive off the volatile constituents and to form the coke, passing said volatile constituents through a localized heating zone formed by an electrically conductive carbon, and conducting the electrical current through said carbon particles to heat said carbon particles to incandescence whereby said zone is maintained at a temperature substantially higher than the temperature at which the lignite is formed into coke thereby to convert said volatile constituents so that upon condensation said volatile constituents form a coal tar having the characteristics of high-temperature tars. 30 35
